D. H. Baldwin Company, Cincinnati, Ohio, a corporation of Ohio

Filed Nov. 17, 1966, Ser. No. 4,722

Term of patent 14 years

(Cl. D56—9)

Fig. 1

FIG. 1 is a perspective view of a piano case embodying my new design.

FIG. 2 is a side elevational view thereof.

The dominant features of my design reside in the portions shown in solid lines, the conventional keyboard being shown in broken lines.

I claim:

The ornamental design for a piano case, substantially as shown and described.
